Specification of Letters Patent.

Patented Dec. 30, 1913.

Application filed March 10, 1913. Serial No. 753,226.

REISSUED

To all whom it may concern:

Be it known that I, CHARLES A. BOREHAM, a citizen of the United States, residing at Coalinga, in the county of Fresno and State 5 of California, have invented new and useful Improvements in Vehicle-Springs, of which the following is a specification.

This invention relates to a laminated leaf-spring construction.

10 The object of this invention is to provide an elliptical spring of the multi-leaf type, which shall be more durable, cheaper of manufacture, and higher in efficiency than the present form of springs now generally 15 used.

The invention consists of the parts and construction and combination of parts as hereinafter more fully described and claimed, having reference to the accompanying drawings, in which—

Figure 1 is a side elevation of the spring. Fig. 2 is a section of same, partly broken away. Fig. 3 is a perspective view of the inner end of a leaf-spring, showing the interlocking means.

The purpose of this invention is to provide a multi-leaf-spring, which is particularly adapted for use in connection with vehicles. In constructing laminated springs 30 of this type it is very essential that the plates or leaves in the spring should decrease on a regular scale of lengths, in order that the spring may be of equal strength throughout and of sufficient flexibility to yieldingly support the load under all conditions. It happens, however, that the most carefully 35 designed and constructed spring will snap one or more leaves when subjected to more than its maximum compression; thus necessitating 40 ing the complete renewal of the broken sections.

The main object of the invention is to construct a centrally divided spring, which by its construction will considerably lessen the 45 cost of repair, as it will only be necessary to replace one-half of the broken section.

Referring to the drawings: A indicates in general a spring of the laminated or multi-leaf type, which may be constructed to form 50 any of the well-known varieties such as elliptical, semi-elliptical, scroll, etc. I have here shown the spring A constructed as semi-elliptical, which consists of a segment formed of a number of centrally divided 55 leaves or blades 2, arranged to be attached

at the bottom to the axle in the usual manner by a suitable clamp 3, and by the two extremities of the arc, through suitable links or shackles 4 to the body above the axle. The inner ends of the leaves are secured in 60 the clamp 3 and are provided with interlocking grooves or ridges 5 which interlock with each other, for the purpose of further securing the independent leaf sections with relation to each other. The lower ridge 5a is adapted to interlock with a corresponding groove 3a in the lower clamp section, thus providing a positive locking means between the leaf sections and the clamp, independent of the clamping action of same; thus absolutely preventing the removal of any section without first detaching the clamp.

The clamping plates have grooves formed across their outer ends, and rods 6 fit these grooves and bear upon the springs, when the 70 clamping bolts 7 are secured at each side of the springs between the ends and center.

In general practice when removing a broken leaf from the usual leaf-spring, it is 80 invariably found that the leaf is broken either on one side or another of the center; this, however, makes very little difference, as no matter where the leaf is broken it becomes necessary to replace it with a whole new leaf. By constructing a centrally divided leaf-spring, as shown in Fig. 2, it can 85 easily be seen that it will only be necessary to replace a half-leaf in case of breakage, thus materially reducing the repair cost. Furthermore, by constructing the several 90 leaves in interlocking half-sections, as shown, greater durability and efficiency may be secured, as much better results may be obtained when tempering the half-leaf section here shown, as compared with the longer section 95 usually employed.

The spring here shown is similar in appearance to the usual form of spring, and takes no more space than same. The material and finish of the several parts are such 100 as experience and judgment of the manufacturer may dictate.

Having thus described my invention, what I claim and desire to secure by Letters Patent is:

1. In a leaf spring of the character described, a series of two-part superposed leaves abutting at their meeting ends, each of said ends having transverse concavo-convex bends and comprising clamps engag- 110

ing each section whereby the superposed leaf sections are interlocked and held in their relative positions.

2. In a leaf spring of the character described, a series of two part leaves abutting at their meeting ends and having concavo-convex interlocking bends, clamping plates extending in each direction across the meeting ends of the springs, with transverse 5 grooves across their outer ends, cylindrical 10 rods lying in said grooves and bearing upon the springs, and bolts passing through the

clamp plates and the springs, said lower clamp plate having grooves engaging the convexities of the two lowermost spring 15 members.

In testimony whereof I have hereunto set my hand in the presence of two subscribing witnesses.

CHARLES A. BOREHAM.
